CORING APPARATUS

John E. Hoffoss, Houston, Tex., assignor to Reed
Roller Bit Company, Houston, Tex., a corpora-
tion of Texas

Application November 23, 1940, Serial No. 366,820

20 Claims. (Cl. 255—72)

This invention relates to core drilling apparatus and particularly to a means whereby the core barrel or center bit of a retractable core barrel apparatus may be held down and driven.

In the past, retractable core barrels have been held down by mechanical latches, which in some instances served also to drive the barrels. In other cases, suitable splines or keys were used for driving the barrel or the center bit, which replaces coring head on the barrel when drilling without taking a core. In the case of those core barrels which protrude beyond the lower end of the core bit while drilling soft formations springs or the like have also been provided to permit the barrel to retract into the bit when a hard formation is encountered.

One of the difficulties resulting from the use of a latch such as referred to is the possibility of the latch becoming fouled or stuck and failing to release properly when an attempt is made to withdraw the core barrel or center bit. Also, the latching mechanism was necessarily placed above the upper end of the core barrel, necessitating the use of a drill collar or other member above the bit and extending up a considerable distance and providing a keeper for the latch. The spring referred to is also an unwieldy and expensive construction.

It is an object of this invention to dispense with the necessity for the latch and drill collar referred to.

It is a further object of this invention to dispense with the necessity for the spring referred to.

It is a further object to provide an improved driving and hold down means for a core barrel and center bit which will not foul or stick and which may be located within the bit and about the lower end of the core barrel or center bit.

A further object is to provide a mechanical hold down for a core barrel or center bit which will not involve the use of a movable latching part on either the barrel or center bit or the core bit.

Another object is to provide a non-resilient core barrel hold down which will permit retraction of the core barrel when a hard formation is encountered.

Another object of this invention is to provide means whereby the various parts of a core barrel assembly will be kept in tight threaded engagement with each other during the movement of slush downwardly past the core barrel, particularly where the core barrel is driven from a point adjacent its lower end.

Another object is to prevent upflow through the core barrel while it is moving down through the slush into the well.

Other objects and advantages of this invention will become apparent from the following description taken in connection with the accom-

panying drawings wherein are set forth by way of example certain embodiments of this invention.

In the drawings:

Fig. 1 is a longitudinal section through a core bit and core barrel held therein by a device constructed in accordance with this invention;

Fig. 2 is a top plan view of the core barrel assembly illustrated in Fig. 1 as indicated by the line 2—2 of Fig. 1;

Fig. 3 is a side elevation of a part of the core barrel having one portion of the hold down and driving means thereon;

Fig. 4 is a transverse cross section taken along the line 4—4 of Fig. 3;

Fig. 5 is a top plan view of the hold down ring which is mounted in the bit in Fig. 1;

Fig. 6 is a longitudinal cross section taken along the line 6—6 of Fig. 5;

Fig. 7 is a view similar to Fig. 1 but showing a center bit in place in the bit head instead of the core barrel with a core cutter head which is used when coring;

Fig. 8 is a view similar to Fig. 3 but showing a modification;

Fig. 9 is a view similar to Figs. 3 and 8 but showing a still further modification.

Fig. 10 is a fragmentary view of a portion of the hold down means within the core bit shown in Fig. 1;

Fig. 11 is a view similar to Fig. 10 but showing a form adapted to cooperate with the modification shown in Fig. 8.

In Fig. 1 there is shown a drill collar 1 having a core bit 2 secured to its lower end, which bit is constructed in accordance with this invention. The core bit 2 has cutting blades 3 of any desired type and the usual opening 4 therethrough centrally thereof for receiving a core barrel. The upper portion of the opening 4 is larger than the lower portion and secured within this upper portion of the opening as by welding 5 or the like is a hold down and driving ring 6 constructed in accordance with this invention. The interior of the ring 6 is formed with ribs or splines 7 as more clearly shown in Figs. 5 and 6, and these provide driving surfaces 8 facing forwardly with respect to the direction of rotation of the bit when drilling. As shown in Figs. 5 and 6 these ribs are inclined downwardly and rearwardly with respect to the direction of rotation of the bit when drilling, so that the driving surfaces 8 of these splines face forwardly and downwardly.

Referring again to Fig. 1, the core barrel 9 is provided at its upper end with a fitting 10 having a ball check valve 11 therein permitting liquid to flow from the barrel as the core rises therein but preventing liquid from washing downward through the barrel. Fitting 10 is provided on its upper end with a spear head 12 adapted to be

engaged by an overshot or the like on the end of a wire line for removing the core barrel.

The ball valve 11 is normally seated by gravity against the valve seat ring 11-a, but the fitting 10 is provided above the ball valve 11 with a second valve seat 11-b so that when the ball valve 11 is forced upwardly, as by a strong current flowing upwardly past it, it will seat upon the seat 11-b and will close off the passage of fluid up through the core barrel and out through the fitting 10. The purpose of this arrangement is to prevent fluid from flowing upwardly through the core barrel during the time the core barrel is being passed down through the drill stem into operative position. During the taking of a core the flow up past the valve 11 will be insufficient to force this valve against the seat 11-b so that flow from the core barrel during the taking of a core will be permitted.

Above the outlet openings from the fitting 10 and below the spear head 12, this fitting is also provided with notches 10-a each having one straight wall and one curved wall as shown so that when fluid is pumped downwardly past the fitting 10 it will be deflected in a circumferential direction with respect to the fitting 10 and by reaction will cause the fitting 10 to rotate in a clockwise direction when viewed from the upper end. The purpose of this is that when a core barrel is driven from a point adjacent its lower end, as it is in this case, the threaded connections above the drive, if right hand, will tend to unscrew. The tendency toward rotation of the fitting 10, though slight, will tend to keep all of the threaded connections between the parts of the core barrel assembly tight during the taking of a core.

At its extreme lower end the core barrel carries a coring head 13 having teeth 14 thereon adapted to protrude beyond the lower end of the bit 2 to cut the core. Suitable core catchers 15 are carried within the coring head to retain the core in the core barrel once it has been cut.

Between the coring head and the main body of the core barrel is a section 16 more clearly illustrated in Fig. 3, which is the same diameter as the remainder of the core barrel inside but which is formed outside with a series of spiral ribs 17 corresponding in number and pitch to the splines or ribs 7. These ribs 17 are adapted to interfit with the ribs 7 and coat therewith as shown in Fig. 1 to the end that the coring head 13 and the core barrel may be held down in lowermost position while coring, yet capable of yielding upwardly in the event a hard formation is encountered or it is desired to withdraw the core barrel from the well. It is noted that these cooperating splines or ribs will not become clogged, but on the contrary it has been found in actual practice that the slush used in drilling will constantly wash these parts and keep them clean.

The splines 17 are formed on the member 16 by cutting grooves in the original surface of the member 16 and these grooves terminate at their upper ends in squared shoulders 18 which are in Fig. 3 substantially perpendicular to the direction of the splines at their upper ends. The spiral ribs 7 are likewise formed with their upper ends squared and at substantially right angles to the upper end portions of the splines so that when the member 16 moves downwardly into the ring 6 the splines 7 will engage the slots between the ribs 17. The member 16 will be rotated and moved downwardly until the squared-up ends of 75

the splines 7 abut against the squared upper ends of the grooves between the splines 17. It will further be noted that the lower ends of the splines 17 are likewise squared and that due to the respective shapes of the splines 17 and the upper ends of the splines 7, it will be practically impossible for the lower ends of the splines 17 to come in contact with and rest upon the upper ends of the splines 7 with any degree of stability. Instead, if the lower ends of the splines 17 should happen to directly overlie the upper ends of the splines 7 as the core barrel reaches its position within the core bit, the coaction between the upper ends of the splines 7 and the lower ends of the splines 17 will cause the member 16 to rotate slightly in one direction or the other until the splines 17 will enter the spaces between the splines 7.

It is further noted in connection with Figs. 3 and 6 that the splines 7 and 17 are not of uniform width throughout their length. Instead, the splines 7 are narrower at their top than at their bottom ends and the splines 17 are wider at their top than at their bottom ends. Because of this construction, the parts will fit loosely together so as to permit a limited amount of vertical movement of the element 16 when the lower portion of the splines 17 engage the splines 7 but as the member 16 moves downwardly into fuller engagement with the splines 7 the engagement will become tighter so as to allow less free vertical movement.

It will be understood that while the active surfaces on the ribs or splines 7 face downwardly and forwardly and the active cooperating surfaces on the ribs 17 face upwardly and rearwardly with respect to the direction of rotation when drilling, both active surfaces are inclined downwardly and rearwardly with respect to such direction of rotation. It will thus be seen that when the bit is rotated as in drilling, the cooperating surfaces of the ribs or splines 7 and 17 will act not only to drive the core barrel and coring head to rotate with the bit, but will also act to yieldably drive or hold the core barrel and coring head down. The force with which the core barrel is held down will depend upon the degree of inclination of the splines. On the other hand, when the bit is not being rotated, the arrangement shown will offer practically no resistance to a withdrawal of the core barrel.

In some instances it has been found desirable to make the ribs with a greater inclination adjacent the lower ends than adjacent the upper ends thereof as shown in Fig. 8. In this case the lower portions 19 of the splines may be separated from the upper portions 20 by a sharp change of angularity as at 21 or this change may be gradual. With this construction of the splines on the core barrel, the splines in the ring 22 in the bit head will be formed with two corresponding sections 23 and 24 of inclinations similar to the sections 20 and 19 respectively.

Where the form shown in Figs. 8 and 10 is used, the result will be that the coring head may yield upwardly with relative ease when hard formations are encountered because of the slight angularity of the parts 20 and 23 which will be in use while the coring head is fully projected. However, after the coring head has moved upwardly a relatively short distance the parts 19 and 24 of the splines will come into contact with each other and, due to their greater inclination, further upward movement of the core barrel and head will be resisted with a greater force.

The form shown in Figs. 9 and 11 is similar to that just described except that in this case the lower parts 25 and 26 only of the respective splines are inclined and the upper parts 27 and 28 respectively are substantially parallel to the axis of rotation. In this case the portions 27 and 28 will serve merely to drive the core barrel to rotate with the bit when the coring head is fully projected, and the only forces resisting initial upward movement of the barrel will be its own weight plus such force as the slush being pumped through the drill stem against the upper end of the core barrel will apply. However, upon upward movement of the core barrel the parts 25 and 26 will come into contact with a resulting force resisting further upward movement of the coring head.

In Fig. 7 the coring head of Fig. 1 has been replaced with a center bit 29 which is used when drilling without coring. This center bit may be carried on the regular core barrel as shown or on any other type of suitable body member. The center bit has cutting blades 30 which drill out the center of the bottom of the hole, and slush passageways 31 are provided for conveying slush to these blades. At the upper end of the core barrel the valve fitting shown in Fig. 1 is replaced with a simple head 32 having slush passageways 33 therethrough when the center bit is in use.

It will be understood that the splines will serve the same purpose in holding the center bit down while drilling that it does in the case of the core barrel while taking a core.

It will be seen that the hold down and drive is simple and without moving parts to get out of order, that it serves as a hold down and drive only when in use in drilling and will permit ready withdrawal of the core barrel without having to be unlatched.

Having described my invention, I claim:

1. In a coring apparatus, a retractable core barrel, and a part of said core barrel having a rearwardly facing driving surface projecting from the side wall of said core barrel, the lower portion of said surface being inclined downwardly and rearwardly with respect to the direction of rotation of said core barrel while drilling, and the upper portion of said surface being inclined to a lesser degree than the lower portion.

2. In a coring apparatus, a rotary core bit, a retractable core barrel, and cooperating spirally arranged driving splines on said core barrel and in said core bit respectively for driving said core barrel with said core bit, said splines extending downwardly and rearwardly with respect to the rotation of the bit while drilling and the upper ends of the splines in said core bit and the lower end of said splines on said core barrel and the upper ends of said splines in the bit being inclined at an angle other than a right angle to the axis of said core barrel, whereby in the event that the lower ends of said splines on the core barrel contact the upper ends of said splines in said bit as the core barrel is being lowered into place, said core barrel will rotate slightly in one direction or the other and continue its downward movement to its fully engaged position.

3. In a coring apparatus, a rotary core bit, a retractable core barrel and cooperating spirally arranged driving splines on said core barrel and in said core bit, said splines being inclined downwardly and rearwardly with respect to the direction of rotation of said core bit in operation, and the splines in said core bit and the spaces between the splines on said core barrel being tapered in 75

an upward direction whereby they will be brought into closer engagement with each other as the core barrel moves downwardly.

4. In a coring apparatus, a rotary core bit, a retractable core barrel and cooperating spirally arranged driving splines on said core barrel and in said core bit, said splines extending downwardly and rearwardly with respect to rotation of said core bit, the upper ends of the splines in said core bit and the upper ends of the spaces between the splines on said core barrel being squared with respect to the general direction of said splines respectively, whereby they may abut each other squarely as the core barrel moves downwardly to its operating position, to seat said core barrel and limit its downward movement.

5. A core barrel assembly adapted to be lowered through a drill stem and seated within a core bit and to be retrieved through said drill stem, the various parts of said assembly being threadedly connected to each other, said assembly comprising a core barrel and a fitting on the upper end thereof, said fitting having external upwardly facing surfaces inclined with respect to the axis of said fitting in such a direction that when engaged by a downward flow of slush past said fitting they will tend to cause said fitting to rotate in a direction to tighten the threaded engagement between the parts of said assembly.

6. A core barrel assembly adapted to be lowered through a drill stem and seated within a core bit and to be retracted through the drill stem after a core has been taken comprising a core barrel and a valved fitting on the upper end thereof, said valved fitting including a valve chamber opening at its lower end into said core barrel and at its upper end to the interior of the drill stem, and a double seating check valve within said valve chamber, said check valve being adapted to seat normally under the influence of gravity upon its lower seat to prevent down flow into the core barrel but to permit up flow therefrom, said valve being adapted to seat under an excessive up flow through said core barrel against its upper valve seat so as to prevent up flow through the core barrel as during the lowering of the core barrel through the drill stem.

7. In a coring apparatus, a rotary core bit, a retractable core barrel, and cooperating driving parts on said barrel and on said bit for driving said core barrel with said bit, the parts on said core barrel having rearwardly facing driving surfaces projecting from the side wall of said core barrel, the lower portions of said surfaces being inclined downwardly and rearwardly with respect to the direction of rotation of said core barrel while drilling, the upper portions of said surfaces being inclined to a lesser degree than the lower portions, the spaces between the parts on said core barrel being tapered in an upward direction, the parts on said bit having active driving surfaces extending downwardly and rearwardly with respect to the direction of rotation of the bit while drilling, said cooperating parts as they engage being brought into closer engagement with each other as the core barrel moves downwardly.

8. In a coring apparatus, a rotary core bit, a retractable drilling means adapted to extend through the central opening of said bit, and cooperating driving parts on said drilling means and on said core bit for driving said drilling means with said bit, the parts on said drilling

means having rearwardly facing driving surfaces projecting from the side wall of said drilling means, the lower portions of said surfaces being inclined downwardly and rearwardly with respect to the direction of rotation of said drilling means while drilling, the upper portions of said surfaces being inclined to a lesser degree than the lower portions, the spaces between the parts on said drilling means being tapered in an upward direction, the parts on said bit having active driving surfaces extending downwardly and rearwardly with respect to the direction of rotation of the bit while drilling, said cooperating parts as they engage being brought into closer engagement with each other as the drilling means moves downwardly.

9. In a coring apparatus, a rotary core bit, a retractable center bit adapted to extend through the central opening of said bit, and cooperating driving parts on said center bit and on said core bit for driving said center bit with said core bit, the parts on said center bit having rearwardly facing driving surfaces projecting from the side wall of said center bit, the lower portions of said surfaces being inclined downwardly and rearwardly with respect to the direction of rotation of said center bit while drilling, the upper portions of said surfaces being inclined to a lesser degree than the lower portions, the spaces between the parts on said center bit being tapered in an upward direction, the parts on said bit having active driving surfaces extending downwardly and rearwardly with respect to the direction of rotation of the bit while drilling, said cooperating parts as they engage being brought into closer engagement with each other as the center bit moves downwardly.

10. In an apparatus of the character described, a retractable drilling member adapted to be passed downwardly into and retracted from a core bit, and a part of said drilling member having a rearwardly facing driving surface projecting from the side wall of said drilling member, the lower portion of said surface being inclined downwardly and rearwardly with respect to the direction of rotation of said drilling member while drilling, and the upper portion of said surface being inclined to a lesser degree than the lower portion.

11. In an apparatus of the character described, a retractable center bit adapted to be passed downwardly into and retracted from a core bit, and a part of said center bit having a rearwardly facing driving surface projecting from the side wall of said center bit, the lower portion of said surface being inclined downwardly and rearwardly with respect to the direction of rotation of said center bit while drilling, and the upper portion of said surface being inclined to a lesser degree than the lower portion.

12. In a coring apparatus, a core bit, and a part in said core bit having an inwardly extending member carried by said core bit and providing a forwardly facing driving surface inclined downwardly and rearwardly with respect to the direction of rotation of the bit in drilling, said inwardly extending member being of less width at the top end than at the bottom end.

13. In a coring apparatus, a rotary core bit, a retractable core barrel, and cooperating driving parts on said barrel and on said bit for driving said core barrel with said bit, the part on said bit having an active driving surface progressing

downwardly and rearwardly and in a direction opposite to that direction of rotation taken by said drill bit while drilling.

14. In a coring apparatus, a rotary core bit, a retractable core barrel, and cooperating driving parts on said barrel and on said bit for driving said core barrel with said bit, the part on said bit having an active driving surface progressing downwardly and rearwardly and in a direction opposite to that direction of rotation taken by said drill bit, and means to cause a portion of said part on the barrel to move to a position directly beneath a portion of said part on the bit when said barrel moves to its lowermost position in said bit while drilling.

15. In a coring apparatus, a rotary core bit, a retractable drilling means adapted to extend through the central opening of said bit, and cooperating driving parts on said drilling means and on said bit for driving said drilling means with said bit, the part on said bit having an active driving surface progressing downwardly and rearwardly and in a direction opposite to that direction of rotation taken by said drill bit while drilling.

16. In a coring apparatus, a rotary core bit, a retractable center bit adapted to extend through the central opening of said core bit, and cooperating driving parts on said two bits for driving said center bit with said core bit, the part on said rotary core bit having an active driving surface progressing downwardly and rearwardly and in a direction opposite to that direction of rotation taken by said center bit while drilling.

17. In a coring apparatus, a rotary core bit, a retractable drilling member adapted to extend through the central opening of said core bit, and cooperating driving parts on said retractable drilling member and on said bit for driving said drilling member with said bit, both of said parts having active driving surfaces cooperating with the active surfaces on the other parts and progressing downwardly and rearwardly and in a direction of rotation opposite to that direction of rotation taken by said drill bit while drilling.

18. In a coring apparatus, a retractable core barrel, and a part of said core barrel having a rearwardly facing driving surface projecting from the side wall of said core barrel, said surface progressing downwardly and rearwardly and in a direction opposite to that direction of rotation taken by said core barrel while drilling.

19. In an apparatus of the character described, a retractable drilling member adapted to be passed downwardly into and retracted from a core bit, and a part on said drilling member having a rearwardly facing driving surface projecting from the side wall of said drilling member, said surface progressing downwardly and rearwardly and in a direction opposite to that direction of rotation taken by said drilling member while drilling.

20. In an apparatus of the character described, a center bit adapted to be passed downwardly into and retracted from a core bit, and a part on said center bit having a rearwardly facing driving surface projecting from the side wall of said center bit, said surface progressing downwardly and rearwardly and in a direction opposite to that direction of rotation taken by said center bit while drilling.
